KNITTED FABRIC

Jack Shain, Newton, Mass., assignor to Shain & Co., Inc.,
Boston, Mass., a corporation of Massachusetts

Application May 5, 1958, Serial No. 50,745

Term of patent 7 years

(Cl. D47—2)

FIG. 1

Figure 1 is a plan view of the knitted fabric of my new design; Figure 2 is an enlarged detailed view of Figure 1; and Figure 3 is an enlarged schematic edge view showing the rib structure.

The design is of a uniform color and is shown over a dark background to indicate the contrast between the rib chains and the lace-like areas therebetween.

I claim:

The ornamental design for a knitted fabric, substantially as shown and described.
